UNITED STATES PATENT OFFICE.

HORACE WYMAN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PATTERN-MATCHING MECHANISM FOR TAPESTRY-LOOMS.

No. 796,102

Specification of Letters Patent.

Patented Aug. 1, 1905.

Application filed April 9, 1904. Serial No. 202,342.

To all whom it may concern:

Be it known that I, HORACE WYMAN, a citizen of the United States, residing at Worcester, in the county of Worcester and State of Massachusetts, have invented certain new and useful Improvements in Pattern-Matching Machinery for Tapestry-Looms, of which the following is a specification.

My invention relates to improvements in looms for making tapestry carpets in which there is a supplementary warp, with figures printed thereon, to be interwoven in the body of the fabric. The supplementary warp is delivered to the loom greatly in the excess of the delivery of the body-warps, this excess producing the pile or raised surface as the goods are woven, with the figures prominently showing thereon.

In tapestry carpets the figure should be accurately contained in a definite length of the woven fabric in order to match with the figure of other portions of the same fabric when laid side by side.

The object of my invention is to improve upon the construction of tapestry-looms for making tapestry carpets as ordinarily made, and more particularly to provide mechanism for regulating the delivery of the supplementary warp, having figures printed thereon, in connection with the movement of the take-up roll upon which the woven fabric is wound, so as to weave a definite number of tufts of pile in a definite length of fabric.

My invention consists in certain novel features of construction of my improvements, as will be hereinafter fully described.

In my improvements there is a main actuator moved at a normal speed by means of a ratchet-and-pawl or other mechanism from a moving part of the loom to positively rotate the delivery or feed roll, around which the printed warp passes on its way to be woven into the fabric. Said main actuator also moves the take-up roll positively to weave a definite number of tufts of pile in a definite length of the fabric and connects positively the movement of the take-up roll and the movement of the delivery-roll of the printed warp. Said main actuator in my improvements, as herein shown and described, moves the delivery-roll through a compound-gear motion, which in this instance consists of a bevel-gear loosely mounted on the horizontal shaft of the main ac-

tuator, a second bevel-gear loose on said shaft, and a third bevel-gear between two said bevel-gears, with its teeth in mesh with both of said bevel-gears, and mounted on a stud having a hub fast on said shaft to rotate therewith.

The revolution of a vertical shaft of the main actuator turns one of the bevel-gears of the compound-gear motion in one direction, and through the third gear of said compound-gear motion turns the other bevel-gear in the opposite direction and moves, through a worm connected with said last-mentioned gear, a wheel on the delivery-roll to deliver the printed warp to the loom.

The shaft having the compound-gear motion thereon above mentioned has thereon a spur-gear adapted to be turned by other gearing to revolve said shaft and also the third bevel-gear of the compound-gear motion to revolve said gear around the other two bevel-gears of the compound-gear motion, as here shown, in the same direction as the first bevel-gear. The movement of the third bevel-gear will vary the normal movement communicated from the main actuator to the worm and wheel of the delivery-roll proportional to the number of turns which said third gear makes around the two bevel-gears to that of the normal movement of the main actuator. The gearing for turning the spur-gear has a change-gear, which may be changed for gears of different sizes, so that the movement of the shaft and the third bevel-gear of the compound-gear motion may be varied in its relation to the normal movement of the main actuator, as desired.

By means of the mechanism above described between the main actuator and the delivery-roll and the means to change the movement of said mechanism to regulate the speed at which the delivery-roll will turn I am enabled to deliver any desired quantity of warp at each motion of the loom with the greatest accuracy.

The main actuator for turning the delivery-roll is adapted to turn the take-up roll of the loom in the same positive way, due allowance being made for the relative speeds at which the delivery-roll and take-up roll turn, for the greater length of warp necessary to be delivered to produce the pile on the face of the fabric, and by combining the mechanisms for turning the delivery-roll and the take-up roll

I am enabled to weave tapestry carpets with figures on their face which will match perfectly one figure with another.

The main actuator is provided with a reversing mechanism, by means of which the take-up roll and the delivery-roll can be moved backward step by step while the loom is being operated to correct any imperfections which may have occurred in weaving.

The printed warp on its way from the delivery-roll to be woven in the fabric passes through a set of heddles, which raise and lower said warp from one shed to the other, and in order to keep a tension on said warp in passing from one shed to the opposite shed and to positively hold said warp at each beat of the lay in the different positions of the heddles I provide a movable tension-bar, which moves positively back and forth as the figured warp is slackened or tightened in the different positions of the harnesses.

I have only shown in the drawings sufficient parts of a loom with my improvements applied thereto to enable those skilled in the art to which my invention belongs to understand the construction and operation thereof.

Referring to the drawings, Figure 1 is a plan view of the delivery mechanism of the printed warp and its operating mechanism and also of the take-up roll and the operating mechanism looking in the direction of arrow *a*, Figs. 2 and 3. Fig. 2 is, on an enlarged scale, a side view of the parts shown in the upper part of Fig. 1 looking in the direction of arrow *b*, same figure. Fig. 3 is, on an enlarged scale, a side view of the parts shown at the bottom in Fig. 1 looking in the direction of arrow *b*, same figure. Fig. 4 shows, on an enlarged scale, the parts shown at the right in Fig. 1 looking in the direction of arrow *c*, same figure. Fig. 5 is a central longitudinal vertical section through the lower horizontal shaft shown in Fig. 2 and the mechanism connected therewith. Fig. 6 is a side view of the double-pawl ratchet mechanism shown in Fig. 3 looking in the direction of arrow *d*, same figure; and Fig. 7 is a detached side view of the change-gearing shown in Fig. 2, taken at a point indicated by line 7 7, Fig. 2, looking in the direction of arrow *e*, same figure.

In the accompanying drawings the main actuator referred to above is shown as consisting of the horizontal shaft 1, Fig. 3, mounted in bearings 1' and having the bevel-gear 2 on one end meshing with the bevel-gear 3 on the lower end of the vertical shaft 4, mounted in bearings 4', and having the bevel-gear 5, fast thereon, meshing with the bevel-gear 6, fast on the hub 7 of the bevel-gear 7, journaled in bearings 7", and loosely mounted on the shaft 8. A second bevel-gear 9 has a hub 9' and is loosely mounted on the shaft 8 and has fast on its hub 9' the worm 10, (see Fig. 5,) which meshes with the worm-

wheel 11, fast on the end of the journal 12 of the delivery-roll 13. The said parts comprising the main actuator have a movement communicated thereto in either direction through the two ratchet-wheels 14 and 15, Fig. 3, fast on the shaft 1, and the two pawls 16 and 17, pivotally mounted on a pin 18' in one end of an angle-lever 18, loosely mounted on the shaft 1 between the ratchet-wheels 14 and 15. The other arm of said angle-lever 18 is connected by a link 19 with a lever 20, fast, in this instance, on the fulcrum 21 of the lay. (Not shown.) One or the other of the pawls 16 and 17 is moved by the operator out of engagement with its ratchet-wheel 14 or 15, according to the desired direction of movement of the shaft 1 and the mechanism connected therewith.

On the shaft 8, between the two bevel-gears 7 and 9, is fast the hub 22' of a stud 22, on which is loosely mounted a bevel-gear 23, extending between and meshing with the two bevel-gears 7 and 9 and forming the third gear of the compound gearing. (See Fig. 5.) A bolt 23' and washer 23" serve in this instance to hold the bevel-gear 23 loosely on the stud 22. The revolution of the gear 7 in one direction will communicate through the bevel-gear 23 a movement to the bevel-gear 9 and worm 10 in an opposite direction.

On the shaft 8 is loosely mounted a sleeve 24', journaled in bearings 24", (see Fig. 5,) having fast on one end thereof a disk 25, having recesses 25' therein to receive the end of a spring-actuated pin 26, having a head 26' thereon, and mounted to have a longitudinal motion in a collar 27, fast on the shaft 8. (See Fig. 5.) On the extreme end of the shaft 8 is a hand-wheel 29. On the inner end of the sleeve 24' is a spur-gear 24. (See Fig. 5.) By means of the spring-actuated pin 26 and the disk 25 the sleeve 24', having the spur-gear 24 thereon, is connected with the shaft 8 to cause said shaft to revolve with said spur-gear 24 or is disconnected to allow the shaft 8 to be revolved independently of the gear 24. The spur-gear 24 meshes with a pinion 30, which is mounted on a stud 30', carried on a stand 30", having a hub 30''' loosely mounted on the shaft 8 and having an arm 30''' adjustably connected by a bolt 31' with the slotted end 31" of a stand 31, secured to the loom-frame. (See Fig. 7.) The pinion 30 meshes with a change-gear 32, the hub 32' of which is secured by a set-screw 32" on the end of the shaft 33, mounted to revolve in bearings 34. For the gear 32 other gears of different sizes may be substituted to change the speed of the spur-gear 24 and the shaft 8. On the opposite end of the shaft 33 is fast the hub 35' of a worm-gear 35, which meshes with and is driven by the worm 36, fast on the upper end of the vertical shaft 4. (See Figs. 1 and 2.) The revolution of the vertical shaft 4, through worm 36, worm-gear 35, shaft 33,

change-gear 32, pinion 30, and spur-gear 24, sleeve 24', disk 25, spring-actuated pin 26, and collar 27, fast on the shaft 8, communicates a rotary motion to the shaft 8 and causes the bevel-gear 33, on the stud 22, having the hub 22' fast on the shaft 8, as shown in Fig. 5, to revolve with said shaft, and at the same time, through the revolution of the vertical shaft 4, the bevel-gears 5 and 6, and the bevel-gear 7, rotary motion is communicated through bevel-gear 23 to the bevel-gear 9 and the worm 10 to turn the wheel 11 on the journal 12 of the delivery-roll 13. The turning of the shaft 8, carrying the intermediate gear 23 one turn around the gear 7 in the same direction as the gear 7 rotates, will cause the gear 9 to lose two turns of the rotation of the gear 7 in the transmission and diminish the speed of rotation of the delivery-roll 13.

On one end of the lower horizontal shaft 1 of the main actuator mechanism is fast a worm 37, (see Fig. 3,) which meshes with and turns a worm-gear 38, fast on the journal 39 of the take-up roll 40, onto which the woven fabric passes from the cloth-plate 41.

From the beam 42, having journals 42' mounted in suitable bearings, the printed warp 43 (shown by broken lines in Fig. 4) passes around the let-off or delivery roll 13 and over a roll 45, held in frictional engagement therewith, to the tension-rod 46 and from thence through the harness 47 to the body of the fabric. (Not shown.) The roll 45 has journals 45', extending out from its ends, which are supported on the upper edges of inclined arms 45'', each having a hub rotatably mounted on a stud 45^a and adjustably secured at its inner end by a bolt 45^{a'}, extending through a slot 45^b in the lower end of a bracket 45^b, secured to the frame. (See Fig. 4.) The tension-rod 46 is in this instance supported in the lower end of an arm 48, the hub 48' of which is mounted on a stud 49. Extending up from the hub 48' is an arm 48'', having a slot 48''' therein, with which is connected a stud 50' on the end of a connector or link 50. The other end of said connector 50 is pivotally connected with an arm 51, the hub 51' of which is fast on a rock-shaft 52. On said rock-shaft 52 is fast an arm 53, which is pivotally connected at 53' by a link 54 to the upper end of the harness 47, as shown in Fig. 4. The usual up-and-down movement of the harness 47, common to looms, to form sheds as required by the movement of the loom in weaving, will at the same time, through link 54, arm 53, rock-shaft 52, arm 51, link 50, and arm 48'', communicate movement to the arm 48 to regulate the tension of the rod 46 on the printed warp 43.

On one of the journals 42' of the beam 42 is fast a grooved pulley 55, around which passes a band 56. One end of said band is connected with a stationary hook 57, and the other end of said band is connected with a spiral spring 58, which spring is connected by a link

59 with the hook 57. By means of the band 56 and spring 58 tension is applied to the pulley 55 and the beam 42.

From the above description in connection with the drawings the operation of my improvements will be readily understood by those skilled in the art. Through the main actuator mechanism, comprising the parts above referred to, rotary motion is communicated to the delivery-roll, and through the supplemental mechanism, of which the bevel-gear 23 forms a part, greater or less speed is communicated to the delivery-roll, as desired, by simply changing the change-gear 32.

The operation of the mechanism is such, with the gearing so proportioned, through the travel of worm 36, worm-wheel 35, shaft 33, gears 32 and 24, that twenty rotations of gear 7 and one rotation of shaft 8 will transmit eighteen rotations to the gear 9 and with the change-gear 32, having forty teeth thereon, to turn the shaft 8. If a change of one tooth in said gear is made, it will make a change of one-fortieth of a rotation of the shaft 8 and will cause the twenty rotations of gear 7 to lose or gain two-fortieths or five-hundredths part of a rotation transmitted to gear 9, according to whether the change-gear 32 is made with one tooth more or with one tooth less than the change-gear having forty teeth. Five-hundredths part of a rotation of the eighteen rotations of gear 9 will make a change of one in three hundred and sixty (360) parts. For example, if the design of a carpet is thirty-six inches long and has three hundred and sixty rows of tufts or piles in its whole length each change of a tooth of the change-gear 32 will change the length of the woven design one three-hundred-and-sixtieth, or one tuft in the whole length.

It will be understood that the details of construction of my improvements may be varied, if desired, from what is shown and described.

The compound gearing instead of being composed of toothed gearing may be made of frictional gearing or surfaces and instead of being composed of the particular parts shown and described may be any equivalent mechanism by which the movement of the delivery-roll from the main actuator may be varied.

I do not limit my invention to tapestry-carpet looms, as my improvements may be used on other kinds of looms.

Having thus described my invention, what I claim as new, and desire to secure by Letters Patent, is—

1. The combination with a main actuating mechanism to normally rotate a roll or spool, of controlling mechanism to move said roll or spool at a changed speed from its normal movement, and intermediate change-gearing to adjust said speed as desired, substantially as shown and described.

2. In a loom having a delivery-roll of a warp-delivery mechanism, a normally mov-

ing primary shaft, combined with movable intermediate mechanism, the combined movements of the two turning said feed-roll, at a changed speed from its normal speed, substantially as shown and described.

3. In a loom having a delivery-roll of a warp-delivery mechanism, a rotatable main mechanism, and intermediate mechanism to turn said delivery-roll, and means to adjust the speed of the intermediate mechanism to vary the speed of said roll, substantially as shown and described.

4. In a loom provided with a warp-delivery roll, a normally moving main actuating-shaft, and an intermediate mechanism, and changeable gearing by which the combined movement of the actuating-shaft and intermediate mechanism may be varied, substantially as shown and described.

5. In a loom provided with a warp-delivery roll and means to move it, a main driving-shaft, and a secondary mechanism, and a series of change-gearing to modify the movement of the main shaft, to move said delivery-roll, substantially as shown and described.

6. In a loom provided with a warp-delivery roll, a normally-moving main shaft, and a modified - moving intermediate mechanism, and means to vary the speed of said intermediate mechanism, to produce any desired movement of the delivery-roll, substantially as shown and described.

7. A main actuating means to turn a de-

livery-roll,secondary or intermediate mechanism to modify the movement of said delivery-roll, and intermediate change-gearing to produce any desired relative movement between the main actuating means and the delivery-roll, substantially as shown and described.

8. In a loom, a delivery-roll, a take-up roll, and intermediate actuating mechanism between the two rolls, with means to change the relative movements of said rolls, to accurately deliver a definite amount of material, from the delivery-roll for a definite length of the fabric, measured on the take-up roll, substantially as shown and described.

9. In a loom, a positively-moving delivery-roll, a take-up roll, and intermediate mechanism between the two rolls provided with a ratchet-and-pawl mechanism to move said rolls in one direction, and a reversely-acting ratchet-and-pawl mechanism to move said rolls in an opposite direction, substantially as shown and described.

10. In a loom provided with a supplementary warp, a positively-moving delivery-roll therefor, a movable tension-bar for said supplementary warp, to positively hold said warp at each beat of the lay for the different positions of the harness of said supplementary warp, substantially as shown and described.

HORACE WYMAN.
